(57) **CLAIM**

The ornamental design for a screwdriver handle, as shown and described.

DESCRIPTION

FIG. 1 is a perspective view of a screwdriver handle showing our new design;

FIG. 2 is a left side elevational view thereof, the right side elevational view being a mirror image thereof;

FIG. 3 is a top side elevational view thereof;

FIG. 4 is a bottom side elevational view thereof;

FIG. 5 is a front end elevational view thereof; and,

FIG. 6 is a rear end elevational view thereof.

The broken line representations of portions of the screwdriver handle in FIGS. 1–6 do not limit the claimed design.
